VALVE CONTROL FOR FUEL OIL HEATERS

Herbert G. Johnson, Haverford Township, Delaware County, Pa., assignor to Zallea Brothers & Johnson, Wilmington, Del., a partnership consisting of James P. Zallea, Sol Zallea, and Herbert G. Johnson

Application January 1, 1944, Serial No. 516,609

5 Claims. (Cl. 257—247)

1

This invention relates generally to heat exchange apparatus and more particularly to improvements in the design, construction and operating characteristics of apparatus for pre-heating fluids, such as oils, by the use of a heating medium, such as steam, such an apparatus being shown and described, for example, in United States Letters Patent No. 2,243,593, granted May 27, 1941, to James P. Zallea.

Among the principal objects of the present invention is to provide in such heat exchange apparatus means for by-passing the fluid to be pre-heated directly through one end of the apparatus, thereby not only avoiding the necessity of interrupting the flow of the fluid when it is desired to service or repair the heat-exchanging apparatus, but also rendering it possible to deliver the fluid as desired without requiring it to be circulated through the heat-exchanger.

A further and important object of the invention is to provide in a heat-exchanger by-passing means for the fluid to be pre-heated which is operative in such manner that the fluid is either directed through the heat-exchanger for circulation through the interconnected heat transfer tubes thereof or through a direct passage between the fluid inlet and outlet connections of the apparatus, the said by-passing means being so designed as to insure undirectional flow of the fluid selectively either through the heat transfer tubes of the unit or through the by-pass conduit.

Still a further and important object is to provide a by-passing arrangement of the character hereinbefore described wherein means is provided for relieving the heat-exchanger apparatus of any excessive pressures that may build up in the heat-transfer tubes when the fluid is being delivered through the by-passing conduit, this means being operative automatically to vent the fluid in the heat-transfer tubes to the by-pass conduit should the pressure of the fluid in the tubes exceed that of the fluid being by-passed.

Another and important object of the present invention is to provide valve means for controlling the supply of the heating fluid, such as steam, to the individual steam injection tubes of the heat exchange apparatus, the valve means being of such arrangement that any one or more of the steam injection tubes may be so cut-off from the main supply of steam as to provide for accurate control and variation of the heat transfer ratio between the heating medium and the fluid to be heated without necessitating throttling

down of the main supply of the heating medium, e. g. the steam.

Other objects and advantages of the present invention to provide for general improvement in the design, construction and operating efficiency of heat transfer apparatus of the type hereinbefore referred to will appear more fully hereinafter, it being understood that the present invention consists substantially in the combination, construction, location and relative arrangement of parts as described in the following specification, as shown in the accompanying drawings, and as finally pointed out in the appended claims.

15 In the accompanying drawings, which illustrate a preferred form of apparatus constructed in accordance with and embodying the principles of the present invention,

Figure 1 is an elevational view, with parts 20 thereof shown in section taken along the line 1—1 of Figure 2, of a heat exchange apparatus of the present invention, the by-passing means being shown in position for directing the fluid through the by-pass conduit;

25 Figure 2 is a front elevational view thereof;

Figure 3 is a rear elevational view thereof;

Figure 4 is a partial view of the apparatus as shown in Figure 1 showing the by-passing means in position for normal operation of the apparatus;

30 Figure 5 is a sectional view taken on the line 5—5 of Figure 4; and

Figure 6 is a sectional view taken on the line 6—6 of Figure 4.

35 Referring now more particularly to the drawings, it will be observed that the apparatus of the present invention is in the form of a multiple unit heat-exchanger which essentially consists of a plurality of units 10, 11, 12 and 13, of similar construction disposed in laterally spaced pairs arranged in vertically spaced relation. Thus, the units 10 and 11, comprising one of the laterally spaced pairs thereof, are vertically spaced with respect to the laterally spaced pair of similar tubes 12 and 13. However, it will be understood that the general arrangement and relative disposition of these tube units 10 to 13 may be varied, as desired, to suit different installation conditions and space limitations.

40 Generally, each of these tube units 10 to 13 includes a main conduit 14 for conducting through the heat exchange apparatus the fluid, such as oil, which is to be pre-heated, the forward ends of these main conduits 14 being suitably secured, as at 15, within a vertically dis-

posed supporting plate 16, these tubes 14 being further supported in the fixed relation shown by means of one or more longitudinally spaced supporting members 17.

Immediately associated with the plate 16 is a second plate 18, the inner face of which is recessed to provide communicating passages between the forward ends of the conduits 14 of the tube units 10 and 11, as well as between the forward ends of the conduits 14 of the tube units 12 and 13. The rear end of the conduit 14 of the tube unit 10 is provided with a lateral opening 19 in communication with the oil inlet connection 20, while the rear end of the conduit 14 of the tube unit 13 is similarly provided with a lateral opening 21 in communication with the oil outlet connection 22. The rear ends of the outer main conduits of the tube units 11 and 12 communicate with each other by way of an interconnecting conduit 23^a (see Figure 3), in view of which it will be apparent that the fluid, such as oil, to be pre-heated, may be caused to circulate through the heat-exchanging apparatus as follows: through the intake 20, thence forwardly through the main conduit of the tube unit 10, thence by way of the recess 23 in the plate 18 to the main conduit of the tube unit 11 and rearwardly through said conduit to the rear end of the main conduit of the tube unit 12, thence forwardly of said latter conduit and by way of the recess 24 in the plate 18 to the front end of the main conduit of the tube unit 13, and thence rearwardly of this last-mentioned conduit to the outlet connection 22. The fluid to be heated, which is delivered to the heat-exchanger apparatus by the inlet connection 20 and discharged therefrom by way of the outlet connection 22, is thus normally caused to circulate through the units 10, 11, 12 and 13 in the order named, successive pairs of these units being in connection with one another by way of the connecting passages 23 and 24 provided in the inner face of the tube plate 18.

This tube plate 18 constitutes the support for a plurality of finned heat radiating tubes 25, each of these tubes being disposed concentrically within the outer main conduit 14 of each of the tube units 10, 11, 12 and 13. As appears most clearly in Figures 1 and 4, the outer or rear extremities of each of the finned tubes 25 is closed, as at 26, while the opposite or inner end thereof is open, as at 27, for communication with an exhaust chamber 28 formed between the intermediate tube plate 18 and a diaphragm 29 spaced therefrom and supported in position by an outer plate or head 30. The chamber 28, with which the forward ends of the heat radiating tubes 25 commonly communicate, is provided with one or more discharge ports 31. In the arrangement of Figure 1, two such ports 31 are shown.

Supported by the diaphragm plate 29 are a plurality of steam injection tubes 32 which respectively extend interiorly of and are disposed concentrically within the finned heat radiating tubes 25, these steam injection tubes being each open at both ends thereof, as at 33 and 34, the front ends 35 of these tubes being all in communication with a chamber 35 provided between the diaphragm plate 29 and the outer or front head 30. This latter chamber 35 is preferably formed by providing the said head 30 with a recess in the rear face thereof which is closed by the diaphragm plate 29, the main plates 16, 18 and 30 being securely clamped together by a plurality of circumferentially spaced securing bolts 75

36. The outer head 30 is provided with an opening 37 constituting a steam inlet to the chamber 35.

In the normal operation of the heat-exchanger apparatus as just described, steam employed as the heating medium is introduced to the apparatus by way of the inlet 37, while the liquid to be pre-heated, such as oil, is introduced by way of the inlet connection 20, the heat transference from the heating medium to the fluid to be heated being effected by circulating both fluids continuously through the apparatus. The steam which is supplied by way of the inlet 37 enters steam chamber 35 and is commonly delivered therefrom into the inner steam injection tubes 32. The steam so delivered into the tubes 32 discharges from the rear open ends 34 thereof against the closed ends 26 of the heat radiating tubes 25 and is returned by the latter into the chamber 28 from whence it is finally discharged by way of the steam outlets 31.

The oil to be heated, which is introduced into the apparatus by way of the inlet 20, traverses the annular spaces formed between the finned heat radiating tubes 25 and the outer main conduits 14, the oil being circulated through the apparatus by way of the tube units 10, 11, 12 and 13 in the order named, for final discharge therefrom by way of the oil outlet 22.

30 As has been pointed out hereinbefore, it is among the objects of the present invention to provide in the heat-exchanger of the character described, means for by-passing the oil through a passage extending directly from the oil inlet 20 to the oil outlet 22, such by-passing of the oil being effected without necessitating disruption of the off line leading from the source of its supply to the point of its application and use. As will presently appear, this by-passing arrangement is so included in the heat-exchanger apparatus as a part thereof as to enable the oil to be by-passed with respect to the heat-exchanger apparatus without necessitating removal of the apparatus from the oil line. In fact, the arrangement is such that upon suitable operation of the by-passing means, the heat-exchanger apparatus per se may be completely dismantled for purposes of maintenance, service and repair without any interruption in the supply of oil through its main feeder line. Essentially, the by-passing means is of such construction and operation as to permit the oil to be readily diverted from its normal circulatory path through the heat-exchanger apparatus to and through a path of flow extending directly between the inlet and outlet connections of the heat-exchanger apparatus.

The means for effecting this desired by-passing operation is of the construction and operation now to be described. As most clearly appears in Figures 1 and 4 to 6, the rear portions of the outer main conduits 14-14 of the vertically spaced tube units 10 and 13 are connected together by a vertically extending passage 40, preferably formed by providing each of said conduits with registering elliptical openings 41 and 42 and then interconnecting said openings by an elliptically shaped tube 43. Both of the conduits 14-14 so connected together by the intercommunicating elliptical passage 40 are respectively provided with annular valve seats 44 and 45, each of which is disposed immediately to the rear of the closed end 26 of the finned heat radiating tube 25 disposed within the particular oil conduit 14. The conduit 14 of the tube unit 10 is additionally

provided with a second rearwardly spaced annular valve seat 46.

The rear extremities of the oil conduits 14-14 of the tube units 10 and 13 are each closed in any suitable manner, and each carries a rearwardly projecting arbor 41 having a centrally disposed internally threaded bearing 48 for a threaded valve stem. These valve stems, respectively designated by the numerals 49 and 50, extend axially through suitable stuffing boxes 51 provided in the rear ends of the said conduits 14-14 and are respectively provided at their forward ends with valve members 52 and 53. The valve member 52 is of the single seating type for coaction with the annular valve seat 44, while the valve 53 is of the double seating type for selective coaction with either of the annular valve seats 45 or 46. Suitable hand wheels 54 are provided at the outer rear extremities of the valve stems 49 and 50 for operation thereof, and in order to insure synchronous operation of the valves, the valve stems are joined together for common actuation thereof by either one of the hand wheels 54 through the medium of a sprocket chain 55 and sprocket gears 56 respectively secured to the valve stems.

In the operation of the oil flow control valves, it will be apparent that when these valves are positioned as shown in Figure 4, wherein the valve 53 is closed upon its rearmost seat 46 and both valves 52 and 53 are entirely free of their respective valve seats 44 and 45, the oil entering the inlet 20 of the heat-exchanger apparatus is caused to circulate through the several tube units thereof for final discharge therefrom by way of the outlet 22. Inasmuch as the passage through the valve seat 46 is closed by the valve 53, no part of the oil may pass through the apparatus otherwise than as just described. However, when the valves are moved into their positions as shown in Figure 1, the circulation of the oil through the tube units 10, 11, 12 and 13 is interrupted and the oil can then pass from the inlet 20 to the outlet 22 of the apparatus only by way of the by-pass connection 46, as indicated by the arrows in Figure 1.

In order to relieve the oil circulating tubes of the heat-exchanger apparatus of any excessive pressures that may develop therein when the valves 52 and 53 are closed, as shown in Figure 1, any suitable means may be provided in association with the valve 52 for permitting it to be opened under such excessive pressure and so vent the oil contained in the circulating tubes into the discharge connection 22 of the apparatus. A suitable means for so relieving such pressure is illustrated in Figures 1 and 4 wherein it will be observed that the valve stem 49 is constructed of two parts 49^a and 49^b, the part 49^a having secured thereto a cylinder or the like 57, into the forward end of which projects the part 49^b of the valve stem. This part 49^b carries a piston element 58 between which and the rear end of the piston casing 50 is disposed a coiled compression spring 59. It will be apparent that if any excessive oil pressure develops within the tube unit 13, such pressure will cause the valve 52 to move rearwardly of its seat 44 against the pressure of the spring 49, thereby affording relief for any such excessive pressure, the bias of the coiled spring 59 being normally sufficient to maintain the valve 52 closed so long as the pressure of the oil contained in the tube unit 13 does not exceed that which flows through the by-pass conduit. Due to the fact that the valve stems 49 and 50 are geared to-

gether for synchronous operation, it will be apparent that there is no possibility of the valve 52 being closed without at the same time closing the valve 53, or of the valve 53 being opened without at the same time opening the valve 52. But even should the opening of the valve 52 lag somewhat behind the opening of the valve 53, the relief means operatively associated with the valve 52 is sufficient to preclude the building up of any excessive pressure in the oil circulating tubes of the apparatus.

Referring now to the front end of the heat exchange apparatus as shown more particularly in Figure 1, it will be observed that the front plate 30 of the steam chest 35 supports a plurality of valve members 60 which are selectively operable to control the passage of steam into the several steam injection tubes 32. To this end, each of these tubes 32 is suitably provided at its outer steam receiving end with an annular valve seat 61 which is adapted to be engaged by a conical valve member 62 fitted on the inner end of a valve stem 63. This valve stem 63, which carries at its outer end an operating hand wheel 64, is threaded or otherwise supported for axial movement within a bearing member 65 removably secured within the plate 30. A suitable stuffing box 66 is provided, as shown, for preventing the escape of steam from the steam chamber 35 outwardly by way of the valve stem 63. Preferably, the bearing members 65 for the several valve members 60 are threaded into the plate 30 for ready removal therefrom and are of such dimension that when removed from the plate 30, they afford openings of sufficient size to provide for ready access to the steam injection tubes 32 and permit the withdrawal therethrough, if desired, of the steam injection tubes for purposes of repair and replacement.

It will be apparent that the provision of these valve members 60 for selectively controlling the supply of steam to the individual steam injection tubes 32 renders it possible to regulate and accurately control the temperature of the fluid to be heated by the apparatus as it circulates through the several tube units thereof, all without necessitating any changes or adjustments of the temperature and pressure of the steam at its source of supply to the steam chamber 35. Thus, should it be desired to utilize the heat exchange apparatus so as to heat the fluid circulated therethrough to the fullest possible extent determined by the temperature of the steam supplied to the apparatus, all of the valve members 60 will be opened to thereby permit the steam supply to the chamber 35 to freely enter all of the steam injection tubes 32. On the other hand, should it be desired to attain for the fluid circulating through the heat exchange apparatus a lower temperature without effecting any corresponding reduction in the temperature and pressure of the steam supplied from its source, it only becomes necessary to operate one or more of the valve members 60 to close their associated steam injection tubes 32 against the supply of steam therethrough.

It will be understood, of course, that the apparatus of the present invention is susceptible of various changes and modifications which may be made from time to time without departing from the general principles or real spirit thereof, and it is accordingly intended to claim the same broadly, as well as specifically, as indicated by the appended claims.

What is claimed as new and useful is:

1. In a heat exchanging apparatus of the type including a plurality of interconnected fluid circulating tubes through which a fluid to be heated may be continuously circulated and including also fluid inlet and outlet connections in communication with corresponding ends of one pair of said tubes, a by-pass conduit interconnecting said pair of tubes to provide a free passage extending directly between said fluid inlet and outlet connections, a pair of valves disposed in said pair of tubes to close the same against communication with said inlet and outlet connections whereby to render said by-pass conduit effective to direct the fluid therethrough, one of said pair of tubes being provided with a pair of spaced valve seats and the valve associated with said last-mentioned tube being adapted to selectively engage one or the other of said valve seats whereby to direct the flow of fluid either through the circulating tubes or through the by-pass conduit, the other of said pair of tubes being provided with a single valve seat engageable by the other of said valves, and means for insuring synchronous operation of both valves whereby to provide for simultaneous opening or closing of the said ends of said pair of tubes.

2. In a heat exchanging apparatus of the character described, in combination, a plurality of fluid circulating tubes arranged in pairs and connected in series, the corresponding ends of one pair of which are respectively in communication with fluid inlet and outlet connections, the fluid inlet tube being provided with a pair of axially spaced valve ports disposed to either side of the fluid inlet connection and the fluid outlet tube being provided with a single valve port disposed to one side of the fluid outlet connection and corresponding to one of said first-mentioned pair of valve ports, a pair of valves operatively associated with said valve ports and shiftable in one direction to simultaneously engage the corresponding valve ports to close the tubes against circulation of fluid therethrough, and a fluid by-pass interconnecting said fluid inlet and outlet connections to permit the flow of fluid directly therethrough by way of the other of said pair of axially spaced valve ports.

3. In a heat exchanging apparatus of the character described, in combination, a plurality of fluid circulating tubes arranged in pairs and connected in series, the corresponding ends of one pair of which are respectively in communication with fluid inlet and outlet connections, the fluid inlet tube being provided with a pair of axially spaced valve ports disposed to either side of the

fluid inlet connection and the fluid outlet tube being provided with a single valve port disposed to one side of the fluid outlet connection and corresponding to one of said first-mentioned pair of valve ports, a pair of valves operatively associated with said valve ports and shiftable in one direction to simultaneously engage the corresponding valve ports to close the tubes against circulation of fluid therethrough, and a fluid by-pass interconnecting said fluid inlet and outlet connections to permit the flow of fluid directly therethrough by way of the other of said pair of axially spaced valve ports, said valves being shiftable in the opposite direction to simultaneously open said corresponding valve ports for the circulating tubes and close the valve port communicating with said by-pass whereby to direct the fluid through all of said circulating tubes in series.

4. In a heat exchanging apparatus as defined in claim 2 wherein externally accessible means are provided for effecting synchronous actuation of said pair of valves to set the same for fluid flow either through all of the circulating tubes in series or through the by-pass.

5. In a heat exchanging apparatus of the character described, in combination, a plurality of parallel fluid circulating tubes, through which a fluid to be heated may be continuously circulated, one pair of said tubes being terminal tubes and the remaining tubes being intermediate tubes, heating means disposed interiorly of said tubes, supporting means for tubes and heating means at one end of said tubes, said supporting means providing inter-communication between said terminal tubes and the intermediate tubes and providing access to said heating means, one of said terminal tubes having an inlet and the other an outlet at the opposite end, a by-pass conduit interconnecting said terminal tubes at their inlet and outlet ends to provide a free passage extending directly between said inlet and outlet, a pair of valves operatively associated with said terminal tubes at their inlet and outlet ends to close the same against communication with said inlet and outlet to render said by-pass conduit effective to direct the fluid therethrough, one of said terminal tubes being provided with a pair of spaced valve seats and the valve associated with said last mentioned tube being adapted to selectively engage one or the other of said valve seats to direct the flow of fluid either through the circulating tubes or through the by-pass conduit, and means for the synchronous operation of both valves to provide for simultaneous opening or closing.

HERBERT G. JOHNSON.
